Des. 214,700
Patented July 15, 1969

214,700

COMBINED SLIDE VIEWER AND PROJECTOR

Oleg Szymber, Elk Grove, Ill., assignor to GAF Corporation, New York, N.Y., a corporation of Delaware

Filed June 24, 1968, Ser. No. 12,477

Term of patent 14 years

Int. Cl. D16—03

U.S. Cl. D61—1

FIG.1

FIG.2

FIG.3

FIG.4

FIG.5

FIG.6

FIG. 7

FIG. 1 is a front, top and left side perspective view of a combined slide viewer and projector showing my new design;

FIG. 2 is an enlarged front elevational view;

FIG. 3 is a top plan view;

FIG. 4 is a rear elevational view;

FIG. 5 is a left side elevational view;

FIG. 6 is a right side elevational view; and

FIG. 7 is a bottom plan view.

I claim:

The ornamental design for a combined slide viewer and projector, substantially as shown.
